UNITED STATES PATENT OFFICE

2,517,660

AMMUNITION MAGAZINE

Otto R. Haas, Beverly, Mass., assignor to United Shoe Machinery Corporation, Flemington, N. J., a corporation of New Jersey

Original application May 25, 1944, Serial No. 537,267, now Patent No. 2,460,384, dated February 1, 1949. Divided and this application August 5, 1946, Serial No. 688,523

1 Claim. (Cl. 89—34)

1

This invention relates to ammunition magazines and more particularly to magazines from which ammunition is to be loaded automatically into guns of large caliber. This application is a division of application Serial No. 537,267, filed May 25, 1944, Patent No. 2,460,384, dated February 1, 1949, in my name.

The invention is illustrated herein as applied to a gun of large caliber designed for use in an airplane. It is an object of the present invention to provide an improved magazine for accommodating large shells to be fed therefrom to a gun. To this end and in accordance with a feature of the invention, the magazine provides a substantially continuous antifriction supporting surface for sustaining the weight of the shells as they are indexed in the magazine to a release station from which they are withdrawn to be fed into the gun. This supporting surface is illustrated as being formed of a plurality of small rolls arranged in staggered relation over which the shells pass as they are indexed through the magazine. In order to accommodate a large number of shells in the restricted space available in the nose of an airplane, the magazine is kidney-shaped and is located above and to the rear of the gun and substantially concentric therewith. The magazine provides a pair of kidney-shaped tracks each of which is formed of a pair of members between which the shells are confined for movement and shell-engaging members are positioned between each pair of shells and are interconnected and guided for movement in a path parallel to the path of movement of the shells thereby to feed the shells in a step-by-step manner through the magazine.

The lower central portion of the magazine is provided with openings to accommodate the shells upon their movement out of the magazine as they are transferred into ramming position in alignment with the bore of the gun. These openings are normally closed by gates which are opened at a predetermined time during the loading operation to permit a shell to pass therethrough.

The above and other features of the invention, including various novel combinations of parts and details of construction, will now be more particularly described by reference to the accompanying drawings and thereafter pointed out in the claims.

In the drawings:

Fig. 1 is a side elevation of a magazine associated with the breech end of a gun and in which the present invention is embodied;

Fig. 2 is a rear elevation of the magazine,

certain parts being broken away to illustrate the shell-feeding mechanism;

Fig. 3 is a partial front elevation, partly in section, of the magazine, this view being on a larger scale than Fig. 2;

Fig. 4 is a section on the line IV—IV of Fig. 3;

Fig. 5 is a plan view of the front end of the magazine illustrating a part of the drive mechanism by which the shells are fed around the magazine;

Fig. 6 is a section on the line VI—VI of Fig. 5;

Fig. 7 is a plan view of a portion of the cam shaft illustrating certain of the mechanisms operated therefrom;

15 Fig. 8 is a section on the line VIII—VIII of Fig. 6, and

Fig. 9 is a vertical section through the magazine.

The invention is illustrated herein as embodied in a magazine 10 (Fig. 1) associated with a large caliber gun 12 mounted in a frame 14 which in the illustrated embodiment of the invention is carried by the nose 16 of an airplane. The shells are fed in a step-by-step manner in the magazine 20 to a release station from which they are transferred into ramming position in alignment with the bore of the gun and then rammed into the gun as illustrated and described fully in the aforementioned application. The magazine is carried by a frame 18 comprising a pair of side frame members 20 supported at their forward portions on the trunnions 22 of the gun and by a support 24 at their rearward portions. The frame 18 also comprises a rear frame member 26 secured by screws 28 to the rear ends of the side frame members 20.

The magazine 10 comprises a forward wall 30 secured to and extending between intermediate portions of the side frame members 20 and a rear wall 32 carried by the rear frame member 26. The front and rear walls of the magazine are generally kidney-shaped as shown in Fig. 2 and the shells are carried in the magazine as will be described, for movement in a kidney-shaped path. As shown in Fig. 2 the magazine is located above the gun and is generally concentric with the bore of the gun thereby to economize on the limited space available in the nose of the plane. The movement of the shells

40 35 through the kidney-shaped path in the magazine makes it possible to use the maximum number of shells in the limited space available.

45 50 The rearward ends of the shells are supported in the lower run of their path of movement by a track formed of a plurality of antifriction rolls

2

34 arranged as shown in Figs. 3 and 4 in staggered relation thereby to provide a substantially continuous antifriction surface. These rolls are carried by pins 36 (Fig. 4) supported by spaced plates 38 which are in turn carried by bolts 40 secured to and extending forwardly from the rearward wall 32 of the magazine. The upper run of the track is similarly formed of a plurality of antifriction rolls 42 arranged in staggered relation and carried between plates 44 which extend upwardly from a curved plate 46 (Fig. 3) which is carried by a plurality of supporting tubes 48 extending between the front and rear walls of the magazine. These tubes 48 also serve to connect the rear wall of the magazine to the rear frame member 26. For this purpose threaded plugs 50 are fitted into the rearward ends of the tubes 48 and receive screws 52 passing through the frame member 26. Tapered pins 54 pass through laterally extending flanges of the plate 46, tubes 48 and the associated plug 50 thereby to secure the plate and the plugs to the tubes.

Extending around the periphery of the rear wall 32 of the magazine and spaced forwardly thereof is a series of plates 56 (Figs. 3 and 4) which form guideways for the rims R of shells S to prevent axial movement of the shells relatively to the magazine. It will be noted from an inspection of Fig. 3 that the shells are supported throughout the upper run of their path of movement and through a large part of their lower run by the antifriction rolls 34 and 42 thereby to reduce the frictional resistance to their movement. Because of the great weight of the shells it is important in order to obtain a high firing rate and keep the power requirements for feeding the shells at a minimum that all friction in so far as possible be eliminated between the shells and their supporting surfaces. In the upper run of path of movement the shells are supported between rolls 42 in the plate 46 and the flange-engaging plate 56 and in their lower run they are supported between the rolls 34 and the lower edge of the plate 46.

As best shown in Figs. 1 and 4 the forward portions of the shells are guided for movement in a track 62. This track is formed of a central plate member 64 pinned to the tubes 48, this plate member being similar in construction to the plate 46. Antifriction rolls 66 are carried by the upper marginal portion of the plate to support the weight of the shells at their forward portions in the upper run in their path. To constrain the forward portions of the shells against movement upwardly from the rolls 66 a curved plate 68 surrounds the shells, this plate being carried by tubes 70 (Fig. 1) extending between the forward and rearward walls 30 and 32 of the magazine. The lower ends of the plates 68 are secured to brackets 72 extending upwardly from the side frame members 20. These brackets extend inwardly toward each other below the shells in the lower run of the magazine and carry antifriction rolls 74 (Fig. 4) arranged substantially parallel to the rolls 34 (Figs. 3 and 4).

For imparting a step-by-step feeding movement to the shells around the magazine a rod 76 is positioned between each pair of shells, each of these rods carrying a pair of shell-engaging members 78 shaped as indicated in Fig. 3. These rods 76 have secured to their ends T-shaped arms 80, the outer ends of which are connected by links 82 to the adjacent T-shaped arms thereby to provide an endless chain. The links are connected

to the arms 80 by pins 84 which carry rolls 86 arranged to ride on tracks 90 and 92 carried by the front and rear walls 30, 32 of the magazine. These tracks are adjustably secured by screw and slot connections 96 (Fig. 3) to their supporting walls. Screws 98 threaded through bosses 100 carried by the walls, engage shoulders 101 on the tracks to facilitate the accurate adjustment thereof. The tracks 90 and 92 terminate inwardly of the ends of the magazine to permit the rolls 86 to be received between teeth 102 of sprockets 104 carried by shafts 106 journaled between the front and rear walls of the magazine. These sprockets are driven in a step-by-step manner as will be later described to operate the chains formed of the links 82 and arms 80 thereby carrying the rods 76 to move the shells in a step-by-step manner through the magazine. The lower runs of the chains are supported by tracks 108 carried by the front and rear walls of the magazine.

In order to load the magazine the shells are inserted in the upper central portion thereof. To permit the insertion of the shells therein with the flanges of the shells lying between the plate 56 (Fig. 9) and the rear wall 32 of the magazine, the plates 44 carrying the supporting rolls 42 (Fig. 3) terminate at opposite sides of the upper central portion of the plate 46 providing a space therebetween. Mounted for vertical movement in the space thus formed is a depressible plunger 110 urged upwardly into shell-supporting position by a spring 112 thereby normally to form a continuation of the track formed by the rolls 42. The plunger 110 includes a shank portion 114 slidable in a bore in the plate 46. To insert a shell in the magazine the nose is inserted between the plates 64 and 68 (Fig. 9) and the rear end of the shell placed on the plunger 110. This plunger is depressed by force exerted on the back end of the shell until the flange of the shell is below the lower edge of the flange-engaging plate 56 whereupon the shell is moved rearwardly to carry the flange back of the plate 56 so that upon release of pressure on the shell by the operator the plunger 110 forces the shell into the position shown in Fig. 9.

In order to absorb the shock when the nose of the shell is inserted between the plates 64 and 68 a hardened metal insert 116 is provided in the plate 64 in place of the antifriction rolls 66 at this point. The plate 68 which normally constrains the forward portion of the shell against upward movement is recessed at 118 to facilitate insertion of the shell between the plate 68 and the plate 64. In order to hold the shell in position after it has been inserted in the magazine a forwardly extending bracket 120 is secured to the plate 68 and projects below the recessed portion of the plate 68 to engage the shell forwardly thereof.

The shells are fed in a step-by-step manner through the magazine by intermittently driving the sprockets 104 through a distance sufficient to move a shell into position to be removed from the magazine. The shaft 106 carrying the sprockets at one side of the magazine extends forwardly of the front wall of the magazine (Figs. 1 and 5) and is connected by a coupling 122, a variable speed mechanism 124 and beveled gears 126, 128 to a cam shaft 130 journaled in bearings 132 in the side frame members 20. This cam shaft is driven intermittently by a motor 133 and a one revolution clutch 135, as explained fully in the aforementioned application, the

clutch being engaged upon energization of a solenoid 137, to cause an intermittent operation of the shaft 106. The variable speed mechanism 124 may be similar in construction to that illustrated in Letters Patent of the United States No. 2,309,595, granted January 26, 1943, on an application filed in the name of L. E. James. Such a mechanism causes slow starting and stopping of the drive shaft 106 and rapid movement of the shaft between the starting and stopping portions of the cycle of operation.

To permit removal of the shells from the magazine it is provided with a release station at the lower central portion, the tracks being interrupted at this portion and gates 134 (Figs. 3 and 4) being provided for supporting the shells until that portion in the cycle of operations in which the shells are to be removed from the magazine. The gates 134 are formed of curved plates slotted at 136 to receive bolts 138 by which the gates are supported for sliding movement. These bolts are in turn carried by brackets 140, the bracket for the forward gate being carried by the bracket 72 whereas the bracket for the rearward gate is carried by the roll-supporting plate 38. The under surfaces of the gates are provided with rack teeth 142 engageable with gear segments 144, carried by a shaft 146 journaled in bearings 148 in the rear frame member 26 and in bearings 150, 152 (Fig. 6) carried by a transverse frame member 154 secured to the side frame members 20. Upon movement of the segments in the direction of the arrow in Fig. 3 the gates are moved to the left to free the shell supported thereby for downward movement out of the magazine.

The shaft 146 is operated to open the gates 134 in timed relation to the feeding movement of the shells in the magazine. The forward portion of the shaft 146 (Fig. 6) carries a pinion 156 engageable with teeth 158 of a rack 160 mounted for vertical movement in a guideway 162 secured to the front wall of the frame member 154. The rack 160 also has rack teeth 164 arranged for engagement by a gear segment 166 carried by a transversely extending shaft 168 in a forwardly extending bracket 170 secured to the frame member 154. The gear segment 166 is arranged to be connected during normal operation of the apparatus by a pin 172 (Fig. 7) to the rearward end of a lever 174 carried by the shaft 168 and provided at its forward end with a cam roll 176 received in a groove 178 (Fig. 6) in the side of a cam 180 carried by the cam shaft 130. It will be noted that the cam groove 178 is concentric with the shaft 130 through the greater portion of its length so that the gates are in their closed positions except for a short time only during a cycle of operations. During the loading of the magazine the gates must be maintained in their closed positions to prevent the shells from dropping from the magazine at the release station. Accordingly, the gear segment 166 is disconnected from the lever 174 by moving the pin 172 out of engagement with the lever so that movement of the lever will not be imparted to the gear segment 166. In order to position the gear segment in its initial position as shown in Fig. 6 when it is disconnected from the lever 174 the segment is formed with an upwardly extending arm 182 engageable with a stop screw 184 threaded into the bracket 170.

The pin 172 is carried by one end of an arm 186 (Fig. 8) the other end of which carries a guide pin 188 slidable in a bore 190 in the bracket

170. Pivotated to the outer end of the pin 188 is an upwardly extending arm 192 (Fig. 6) the upper end of which is pinned to a forwardly and rearwardly extending shaft 194 to the rear end of which is pinned an arm 196. The upper end of the arm 196 is provided with a handle 198 slidable in a cylindrical portion 200 of the arm and provided at its inner end with a pin 202 arranged to be received in one of a pair of recesses in a plate 206 secured by screws 208 to the front wall 30 of the magazine. With the arm 196 positioned as shown in Fig. 6 the gear segment 166 is connected to the lever 174 by the pin 172 so that upon operation of the cam shaft 130 the gate 134 will be opened and closed. However, if the handle 198 is retracted and the arm 196 swung into its other position the shaft 194 will be turned to rock the arm 192 in a direction to withdraw the pin 172 from engagement with the lever 174, the pin seating in a bore 210 in the bracket 170, thereby locking the gear segment in the position shown in Fig. 6. The gear segment is now disconnected from the lever 174 and the gates will remain closed during operation of the cam shaft 130 to enable ammunition to be supplied to the magazine while preventing shells from dropping from the magazine at the release station.

In describing the operation it will first be assumed that the magazine and gun are empty of shells. In order to load the magazine the control arm 196 (Fig. 6) is moved to withdraw the pin 172 (Figs. 7 and 8) out of engagement with the lever 174 thereby to disconnect the lever from the gear segment 166 so that the cam shaft 130 can be operated without causing the gates at the release station to be opened. This movement of the pin 172 out of engagement with the lever 174 and its simultaneous movement into the bore 210 locks the gear segment 166 in the position shown in Fig. 6. A switch 212 (Figs. 1 and 5) is provided in a circuit to the solenoid 137 so that upon closure of this switch by the operator the clutch 135 is engaged and the cam shaft 130 operates through the gearing 128, 126 and the variable speed transmission 124 to turn the adjacent shaft 106 causing a feeding movement of a shell which has been previously inserted at the loading station as shown in Fig. 9. After each shell is inserted in the magazine the switch 212 is closed whereupon the shells are indexed one step and this operation is continued until the magazine is filled with ammunition.

The arm 196 is now returned to the position of Fig. 6 causing the gear segment 166 to be connected by pin 172 (Fig. 7) with the lever 174 so that at a predetermined time during a subsequent indexing movement the gates 134 (Fig. 3) will be operated to release a shell to the transfer tray which loads it into the gun as described in the aforementioned application.

The provision of the antifriction rolls 34, 42, 66 and 74 for supporting the shells in their feeding movements minimizes the load on the mechanism by which the shells are fed. By making the magazine kidney shaped, as shown in Figs. 2 and 3, a maximum number of shells is accommodated in the limited space available in the nose of the plane in which the gun may be mounted.

It will be understood that during the normal operation of the apparatus the cycle of operation may be initiated by closing a switch to the solenoid 137 or the feeding movement of the shells in the magazine may take place automatically at the close of a firing cycle, as illustrated and described fully in the aforementioned application.

Since the means for controlling the operation of the feeding mechanism forms no part of the present invention, it is not illustrated herein.

Having thus described the invention, what I claim as new and desire to secure by Letters Patent of the United States, is:

A kidney-shaped shell magazine comprising a pair of arcuate parallel vertically-disposed spaced plates, antifriction rolls journaled in the upper margins of the plates and projecting slightly above the upper edges thereof, said rolls being arranged in staggered, overlapping relation to provide a substantially continuous antifriction shell-supporting surface, plate members associated with each of said plates and forming therewith endless arcuate kidney-shaped shell-supporting tracks, means supporting said plate members in equidistant relation to the associated plates throughout the peripheries of the plates, antifriction rolls journaled in the upper margins of those portions of the plate members below the plates, said last-named rolls projecting slightly above the upper edges of the plate members and being arranged in staggered, overlapping relation whereby a pair of continuous kidney-shaped shell-supporting tracks with antifriction shell-

supporting surfaces are provided, said plate members having interrupted portions below said plates to permit egress of shells downwardly from said tracks, retractable gates normally bridging said interrupted portions, means for feeding shells in a step-by-step manner around said tracks to said gates, and means for retracting said gates.

OTTO R. HAAS.
